UNITED STATES PATENT OFFICE.

LEWIS VAN BROWN, OF ASHEVILLE, NORTH CAROLINA, ASSIGNOR OF ONE-HALF TO WILLIAM H. INLOES, OF SAME PLACE.

COMMUTATOR-BRUSH FOR DYNAMOS.

SPECIFICATION forming part of Letters Patent No. 428,073, dated May 20, 1890.

Application filed August 15, 1889. Serial No. 320,819. (No model.)

To all whom it may concern:

Be it known that I, LEWIS VAN BROWN, a citizen of the United States, residing at Asheville, in the county of Buncombe and State of North Carolina, have invented certain new and useful Improvements in Commutator-Brushes for Dynamos and Electric Motors; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a perspective view of a brush. Fig. 2 is a transverse section on line x x , Fig. 1. Fig. 3 shows a modification.

This invention relates to an improved commutator-brush for dynamos and electric motors.

In this kind of devices it has been usual to construct them of several layers of copper held together by several rivets, so as to make practically a solid strip. The present invention consists in the construction hereinafter pointed out.

In the annexed drawings, the letter A indicates the brush, consisting of the several strips a . These strips have an end b flush together where they are held by a rivet c . The other ends are loose and are arranged in sets d and e , one set e being a little back of the other set d , or all the ends may be flush together. Surrounding these loose ends is a keeper or sliding clamp B , held by friction. The better to assure this clamp staying on the brush a nick g may be cut in the top strip, and as the brush wears away and the clamp is slipped upward another nick may be cut to hold it in place. Instead of the nick the clamp may be held by a set-screw. As shown in Fig. 3, a number of these nicks may be made in the top strip before the strips

are put together; but the way shown in Fig. 45 1 is preferable, as the nick can be cut at any place whatever, instead of being put at a predetermined place.

A brush made as described is very elastic, and yet has sufficient stiffness to bear against 50 the commutator-shaft. Provision is made for wear, so as to keep up the efficiency of the brush.

The device thus described is a complete brush in itself, and is an article of manufacture which can be applied to any of the commutators in use. The brush is to be placed in the usual brush-holder, the keeper B being entirely distinct from the ordinary brush-holder, such keeper B being a part of the 60 brush structure.

I am aware that a brush has been made of layers; but as far as I know these layers have been loosely inserted into the ordinary brush-holder, and are only held together by 65 this holder, whereas I use a special keeper distinct from the holder.

Having described my invention, what I claim is—

1. As a new article of manufacture, a commutator-brush consisting of several strips held rigidly together at one end and loosely at the other, and provided with a keeper placed around the loose ends, such keeper being part of the brush structure and distinct 75 from the ordinary brush-holder, as set forth.

2. A commutator-brush consisting of several strips held rigidly together at one end and loosely at the other, the loose ends being held by a sliding clamp and one outside strip 80 having a nick, as set forth.

In testimony whereof I affix my signature in presence of two witnesses.

LEWIS VAN BROWN.
